Patented May 16, 1961

190,326

SCREW-ON CAP CONNECTOR

William G. Schinske, Sycamore, Ill., assignor to Ideal Industries, Inc., Sycamore, Ill., a corporation of Delaware

Filed July 12, 1960, Ser. No. 61,320

Term of patent 14 years

(Cl. D26—1)

Fig. 1.

Fig. 2.

Fig. 3.

Figure 1 is a side elevation of a screw-on cap connector, showing my new design;

Figure 2 is a left end elevational view thereof; and

Figure 3 is a right end elevational view thereof.

I claim:

The ornamental design for a screw-on cap connector, as shown.
